UNITED STATES PATENT OFFICE.

GEORGE E. BATES, OF SYRACUSE, NEW YORK.

LIQUID-DISPENSING DEVICE.

1,283,457.

Specification of Letters Patent.

Patented Nov. 5, 1918.

Application filed May 12, 1916. Serial No. 97,034.

To all whom it may concern:

Be it known that I, GEORGE E. BATES, a citizen of the United States, and a resident of Syracuse, in the county of Onondaga and State of New York, have invented a certain new and useful Liquid-Dispensing Device, of which the following is a specification.

This invention has for its object a liquid dispensing device especially applicable for dispensing liquid soap which device is particularly simple in construction and highly efficient and durable in use, and the invention consists in the combinations and constructions hereinafter set forth and claimed.

In describing this invention, reference is had to the accompanying drawings in which like characters designate corresponding parts in all the views.

Figure 1 is a vertical sectional view of this liquid dispensing device, the parts being shown as in their starting position and the contiguous part of a supporting wall being also shown.

Fig. 2 is a fragmentary view of parts seen in Fig. 1, showing the position of the movable parts when the liquid is being discharged.

This device comprises generally, a container for the liquid, a receiver arranged in position to receive liquid from the container and means for forcing or discharging the liquid from the receiver.

1 designates the container which may be of any suitable form, size and construction.

2 designates the receiver which is a portion of a tubular bracket 3 extending horizontally from a supporting wall 4, and provided with a suitable base 5 which may be secured to the wall 4 in any suitable manner as by screw 6.

As here shown, this bracket is tubular and is formed with a plug 7 located between the ends thereof.

This bracket is here shown as formed with an upwardly extending hollow nipple 8 on its upper side on which is mounted the base 9 of the container 1.

The nipple constitutes the inlet for the receiver 2 and is formed at its lower end with a smaller opening 10 which opens into the receiver 2.

The means for discharging liquid from the receiver 2 comprises a plunger 11 movable in the receiver through the front end

thereof, in line with the axis of the bracket, a space being provided in front of the plunger to receive the liquid to be discharged, the inlet opening 10 opening into the receiver in front of the position occupied by the plunger when in its starting position. The plunger is formed with a stem 12 which extends in front of the end of the tubular bracket and provides a shoulder against which a nut 13 turns for holding the plunger in position, this nut threading into the front end of the tubular part of the bracket.

The outlet for the liquid in the receiver extends in a direction lengthwise of the plunger and is preferably formed in the plunger and opens through the periphery thereof, and means is provided for normally closing the outlet passage and holding the same closed until the plunger has traveled inwardly a predetermined distance far enough to cut off the inlet 10. This outlet passage is preferably closed by a movable valve carried by the plunger, and means is provided for unseating the valve after the plunger has been moved inwardly a predetermined distance.

As here shown, the outlet passage 14 extends substantially coaxially of the plunger and is formed with a laterally extending branch 15 opening through the periphery of the stem of the plunger at point far enough in advance of the front end of the bracket to permit said branch to remain in advance of the front end of the bracket when the plunger is pushed inwardly.

The passage 14 is also formed with a valve seat 16 against which a spring pressed valve 17, carried by the plunger, normally seats, this valve 17 and its spring being located in the enlarged extension 18 of the passage 14 which extension opens at its front end through the front end of the stem of the plunger.

A suitable cap 19, which constitutes the hand engaging part of the plunger, closes the open front end of this passage 18.

The means for unseating the valve includes a rod 20 extending lengthwise of the passage 14, this rod being preferably stationary and carried by the block 7 and having its free end opposed to the valve. The end of said rod is normally spaced from the valve 17 a sufficient distance to permit the plunger to move far enough to cut off the

inlet opening 10 of the receiver 2. Owing to the arrangement of the rod in the passage 14 said rod prevents the passage from becoming clogged.

5 The plunger is normally held from turning by a rod 21 carried by said plug 7 and extending into a socket 22 in the end of the plunger.

23 is a spring located in the receiver in 10 position to resist inward movement of the plunger and to return it to its normal position.

In operation, the parts are normally in 15 their positions shown in Fig. 1 in which the liquid is free to pass into the receiver 2 in front of the plunger 11. Upon pushing inwardly on the plunger 11 it first cuts off the inlet 10, and thereafter the end of the rod 20 unseats the valve 17 so that the 20 liquid is forced through the outlet passage 14 and through the lateral branch 15.

In use, the same hand that forces the plunger inwardly can be conveniently held so that the soap will be discharged into the 25 palm thereof.

This device is particularly advantageous in that it consists in a small number of compactly arranged parts, and further in that owing to the arrangement of the valve and 30 its operating rod obstructing the outlet passage is positively prevented.

What I claim is:

1. A liquid dispensing device comprising 35 a base formed with a passage therein, a container for the liquid communicating with said passage whereby the liquid flows from the container into the passage, a plunger movable in the passage, the plunger having a lengthwise passage opening through its 40 inner end and an angularly arranged outlet port communicating with said lengthwise passage near the outer end thereof, a spring pressed valve arranged to close said lengthwise passage adjacent said port at the outer 45 end of the same, and means for unseating the valve during the inward movement of the plunger, substantially as and for the purpose described.

2. A liquid dispensing device comprising 50 a base formed with a passage therein, a container for the liquid communicating with said passage whereby the liquid flows from the container into the passage, a plunger movable in the passage, the plunger having 55 a lengthwise passage opening through its inner end and an angularly arranged outlet port communicating with said lengthwise passage near the outer end thereof, a spring pressed valve arranged to close said 60 port, and means for unseating the valve during the inward movement of the plunger, substantially as and for the purpose specified.

3. A liquid dispensing device comprising 65 a base formed with a passage therein, a

container for the liquid communicating with said passage whereby the liquid flows from the container into the passage, a plunger movable in the passage, the plunger having a lengthwise passage, and an angularly arranged port communicating with said passage, a spring pressed valve arranged to close said port, and the lengthwise passage, and means for unseating the valve during the inward movement of the plunger, said 70 means extending lengthwise of the lengthwise passage, substantially as and for the purpose set forth.

4. A liquid dispensing device comprising 75 a base formed with a passage therein, a container for the liquid communicating with the said passage whereby the liquid flows from the container into the passage, a plunger movable in the passage, the plunger having a lengthwise passage opening through 80 its inner and outer ends and an angularly arranged outlet port communicating with said lengthwise passage near the front end of the plunger, a cap closing the front end of the passage, a spring pressed valve in 85 said lengthwise passage near the outer end of the same, and arranged to close said port and the passage, the spring of said valve being interposed between the cap and the valve, and means for unseating the valve 90 during the inward movement of the plunger, said means extending lengthwise of the lengthwise passage, substantially as and for the purpose described.

5. A liquid dispensing device comprising 95 a base formed with a receiving passage therein, a container for the liquid having an outlet opening into said receiving passage whereby the liquid flows from the container into the passage, a plunger movable in the 100 passage and arranged to cut off the outlet after said plunger is moved a predetermined distance, the plunger having a lengthwise passage opening through its inner end and an angularly arranged outlet port communicating with said lengthwise passage near the outer end thereof, a spring pressed valve in the passage and arranged to normally prevent the flow of liquid through the port, and means for unseating the valve during the inward movement of the plunger and after said plunger has cut off the outlet 105 of the container, substantially as and for the purpose specified.

6. A liquid dispensing device comprising 110 a base formed with a receiving passage therein, a container for the liquid having an outlet opening into said receiving passage whereby the liquid flows from the container into the passage, a plunger movable 115 in the passage and arranged to cut off the outlet after said plunger has moved a predetermined distance, the plunger having a lengthwise passage opening through its inner end and an angularly arranged outlet 120 port, and means for unseating the valve during the inward movement of the plunger and after said plunger has cut off the outlet of the container, substantially as and for the purpose specified.

7. A liquid dispensing device comprising 125 a base formed with a receiving passage therein, a container for the liquid having an outlet opening into said receiving passage whereby the liquid flows from the container into the passage, a plunger movable in the passage and arranged to cut off the outlet after said plunger has moved a predetermined distance, the plunger having a lengthwise passage opening through its inner end and an angularly arranged outlet 130 port, and means for unseating the valve during the inward movement of the plunger and after said plunger has cut off the outlet of the container, substantially as and for the purpose specified.

port communicating with said lengthwise passage near the outer end thereof, a spring pressed valve in the passage and arranged to normally prevent the flow of liquid through the port, and means for unseating the valve during the inward movement of the plunger and after said plunger has cut off the outlet of the container, said means

extending lengthwise of the passage, substantially as and for the purpose set forth. **10**

In testimony whereof, I have hereunto signed my name, at Syracuse, in the county of Onondaga, and State of New York, this 16th day of February, 1916:

GEORGE E. BATES.
